C. GRAFF

COMBINED CIGAR LIGHTER AND ASH TRAY

Filed Nov. 19, 1926

Inventor

Charles Graff

By his Attorneys

Phelps Lawyer Rev. Kennedy

UNITED STATES PATENT OFFICE.

CHARLES GRAFF, OF NEW YORK, N. Y., ASSIGNOR TO GRAFF, WASHBOURNE & DUNN,
OF NEW YORK, N. Y., A CORPORATION OF NEW YORK.

DESIGN FOR A COMBINED CIGAR LIGHTER AND ASH TRAY.

Application filed November 19, 1926. Serial No. 19,773. Term of patent 3½ years.

To all whom it may concern:

Be it known that I, CHARLES GRAFF, a citizen of the United States, residing in New York city, county and State of New York, have invented a new, original, and ornamental Design for a Combined Cigar Lighter and Ash Tray, of which the following is a specification.

This invention relates to a new, original and ornamental design for a combined cigar lighter and ash tray, and the invention consists in the peculiar shape or configuration of the same, substantially as shown in the accompanying drawing forming a part of this specification, in which—

The figure is a perspective view of the combined cigar lighter and ash tray, showing my new design.

I claim.

The ornamental design for a combined cigar lighter and ash tray as shown.

In testimony whereof I have hereunto set my hand.

CHARLES GRAFF.
